[57] CLAIM

The design of an electronic measurement device, as shown and described.

DESCRIPTION

FIG. 1 is a perspective view of the electronic measurement device;

FIG. 2 is a front elevational view thereof;

FIG. 3 is rear elevational view thereof;

FIG. 4 is right side elevational view thereof;

FIG. 5 is left side elevational view thereof;

FIG. 6 is a top plan view thereof; and,

FIG. 7 is a bottom plan view thereof.
